UNITED STATES PATENT OFFICE.

JOHN GREENWALD HARTLEY, OF PHILADELPHIA, PENNSYLVANIA.

TONGUE-SWITCH HEEL.

1,158,685.

Specification of Letters Patent.

Patented Nov. 2, 1915.

Application filed December 10, 1914. Serial No. 876,397.

To all whom it may concern:

Be it known that I, JOHN GREENWALD HARTLEY, a citizen of the United States, residing at 2505 South Nineteenth street, Philadelphia, in the county of Philadelphia and State of Pennsylvania, have invented a certain new and useful Tongue-Switch Heel, of which the following is a specification.

My invention relates to switches for street use, having a tongue swinging about a depending heel as a pivot and finding their greatest utility in cross-overs and sidings for steam road use.

One purpose of my invention is to protect the parts from moisture and dirt.

A further purpose of my invention is to be free from the necessity of adjustment of the joint, avoiding the objectionable side box required for this adjustment.

20 A further purpose of my invention is to increase the number of wearing surfaces at the heel of the switch and change the distribution of these surfaces.

25 A further purpose of my invention is to utilize the slight dropping of the heel by reason of wear to automatically tighten and recenter the heel pin.

30 A further purpose of my invention is to give the heel pin internal as well as external bearing surface and to fill the space between with oil for lubrication.

35 A further purpose of my invention is to use a depending bearing plug within a hollow depending heel for additional lateral support and bearing surface, preferably giving the plug a taper so that it has a tendency to center the parts as wear of the horizontal contact surfaces allows the heel to settle lower in the switch body.

40 A further purpose of my invention is to utilize atmospheric pressure as a means of restraining the tongue and heel against displacement.

45 A further purpose of my invention is to provide an extended bearing surface in a horizontal plane outside of the heel pin and about it as nearly on a level with the rail flange as possible to support against tipping strains.

50 A further purpose of my invention is to place oil in the upper part of the opening of a hollow heel pin and distribute the oil to the bearing outwardly from this interior

point, preferably maintaining a pool of oil 55 at this point above the adjoining switch body parts to flow throughout the joint and replace oil losses therein.

A further purpose of my invention is to expel oil from a point within the interior of 60 a hollow tongue switch heel in such a direction or in such quantity as to drive out a considerable part if not all the air between the parts and seal the joint with oil.

A further purpose of my invention is to 65 provide annular oil reserve spaces within a switch heel joint and preferably protected from intrusion of foreign matter as a reserve in connection with an oil lubricating system sealing against admission of air or 70 moisture or both to the joint, preferably covering the tongue bed.

A further purpose of my invention is to provide lifting connections for the tongue and heel at a point such that the weight of 75 the tongue on one side of this point shall balance the weight of the tongue and the heel on the opposite side thereof, plus the effective atmospheric resistance to withdrawal of the heel and to provide lifting mechanism 80 for the tongue and heel at this point.

I have preferred to illustrate my invention by but one of the various forms which will occur to switch designers in view of my disclosures herein, selecting one which has 85 proved to be practicable and efficient and which at the same time well illustrates the principles of my invention.

Figure 1 is a top plan view of a switch body, tongue and heel embodying the preferred form of my invention. Fig. 2 is an enlarged top plan view of a part of Fig. 1 with the tongue in a different position from that shown in Fig. 1. Fig. 3 is a top plan view of the tongue and heel shown in Figs. 1 90 and 2. Fig. 4 is an enlarged section of Fig. 2 taken upon the lines 4—4 thereof, looking in the direction of the arrows. Fig. 5 is an enlarged transverse section corresponding to line 5—5 in Fig. 2, showing the switch 100 body and tongue structure with my lifting mechanism in place.

In the drawings, similar numerals of reference indicate like parts.

The tongue switch constructions at present in use, to the best of my knowledge, all utilize some form of tightening device for 105

the pivot. This requires a side take-up for the heel socket and, in practice, is accomplished by placing a wedge or other like mechanism in a box at the side of the switch body.

5 The switch tongue heel pin must be accessible for cleaning at intervals, varying from a few days to several weeks, and must be removed each time it is cleaned. For this 10 reason, the box in which the tightening mechanism is located must be readily accessible and the socket within the switch body must be loosened for removal of the tongue and heel and subsequently tightened at corresponding intervals.

15 Mud and water unavoidably enter and frequently fill the box and cause a great deal of trouble. This is worst in winter time because of freezing of the mud and water in 20 the box. It is often necessary to thaw the box out before the tongue and attached heel can be removed from the switch body.

25 While my invention is designed particularly to present a superior heel joint which requires no adjustment of any character and hence avoids the use of such a box, I aim also to reduce the need and hence the frequency of removal of the tongue and heel for cleaning, and to simplify the removal 30 when it does become desirable.

35 The body 1 shown is of the manganese steel type, cast in one piece, coöperating with the usual filler block 2 and rails 3. The tongue switch bed 4, within which the tongue 5 swings, is the same as in previous 40 constructions and I have made no variation whatever in the surface of the tongue engaged by the wheels. I have shown the bed 4 as laterally extended at intervals, as at 6, to give access for a crow bar, if required, and as affording intermediate side surfaces 7 to support the tongue against the thrust of the car wheels.

45 I prefer to construct the depending tongue heel in the form shown in Fig. 4. For convenience of manufacture of the seat or socket within which the heel of my tongue switch turns, I have inserted a separate manganese steel pin 8 within the preferably cylindrical bore 9 of the body, welding the pin in at 10 after it has been finished to the size desired. This permits me to grind the parts of the pin more conveniently before insertion than I could if this pin structure 50 were integral with the body and also allows a different steel to be used for the pin if desired. It will be recognized that this separation of parts during manufacture is a mere convenience and is not a part of my 55 invention.

60 The heel pin 11 is given a reëntrant surface for greater bearing support and to improve the oil seal against air inlet. It is formed as a depending open-ended cylinder, or approximate cylinder. While I show the

65 sides as of substantially uniform diameter, some taper would not affect the principle of my invention. Any considerable taper would make the fit loose with but slight lifting of the tongue heel pin in the body. 70 This would lose some of the advantages of my invention, though other features invented by me would still be present. The outer surface 12 is preferably a close fit in the interior bore 9 of the switch body at this point 75 and the bottom 13 of the hollow tongue heel pin may have bearing upon the surface 14 of the pin 8.

80 The interior of the depending hollow pin is shown as having two different diameters at 15 and 16 to coöperate with correspondingly different exterior surfaces 17 and 18 upon the body pin. To allow for possible vertical movement because of wear, the lower edge 19 of the surface 15 does not engage the 85 upper edge 20 of the surface 18. For convenience in manufacture and fitting, and so that the grinding of the surface of smaller diameter need not be carried up against the "corner", an annular space 21 is left at this 90 point. Obviously, other annular spaces such as 22 may be left between adjoining surfaces in the same parts wherever desired. In conjunction with the oil filler which I use these annular pockets may have another 95 useful function more fully pointed out later. They may be omitted where their functions are not required or desired or are otherwise secured.

100 The variation in diameters of the upper and lower inner surfaces of the depending tongue switch heel just described is again a matter of convenience merely, for use where the interior heel plug, hereinafter described, is intended to be constructed as a separate 105 piece from the tongue heel. Where the heel and plug are made in separate parts, as illustrated, the difference in diameters shown permits the plug to be inserted as nearly 110 home as may prove desirable before it engages with the surface into which it must be fitted tightly and into which it is seated. There is, however, some advantage in this 115 difference in diameters even where this plug is intended to be cast integrally with the tongue heel as the fit of the heel pin upon the body pin is then not so tight within the first part of the movement during insertion of the heel and the last part during removal of the heel. The structure as thus far described 120 might therefore be summarized as providing a depending open-ended cylinder, or substantially cylindrical collar upon the heel to fit into an annular channel between the body and pin, engaging laterally both inside and 125 outside thereagainst through as large a bearing and wearing surface as possible. The structure as thus far described is itself valuable. Its value is enhanced by the different other features of my invention.

5 I flange the tongue member about and above the heel, as at 23, to provide a surface 24 of greater diameter than the heel pin to rest upon the horizontal surface 25 of the bottom of the tongue bed, which, for convenience, I will call a ledge, whether it be in the same plane as the bottom of the tongue bed or not. It affords extended support against tilting and an additional horizontal wear surface. It also gives an air seal here, in conjunction with the oil herein-
10 after described and protects against the intrusion of foreign matter between the surfaces 9 and 12.

15 The flange 23 bears against the substantially cylindrical sides of the switch bed, shown at 26 throughout about half a circumference to give lateral support about this surface also.

20 It is my purpose to utilize oil between the surfaces both as a lubricant and to secure an air seal and produce a partial vacuum as the heel is lifted. The construction by which the oil is conveniently inserted so as to exclude the air and obtain the best advantage from the oil by filling the interior as completely as possible with the oil, coöperates with another part of my invention designed to give additional bearing surface and have
25 a centering effect.

30 Within the cylindrical heel pin I place a downwardly extending tapered plug 27. This is made as a separate piece from the pin merely for convenience in construction but the separate construction of the parts does not affect my invention. It is made a driving fit within the pin in the location shown. It is supported against vertical pressure by the ring 28 and is shown as
35 tapered at 29 to coöperate with the tapered counterbore 30 upon the upper part of the recess 31 within the body pin. The under surface 32 of the plug flange and upper surface 33 of the body pin preferably do not meet, allowing for vertical movement at this point without wear and providing a space for oil reserve from which the oil will flow into the heel bearing under certain conditions. For example, if there be pressure
40 at this point above that of the atmosphere, such as might be present if any air were trapped in this space and compressed, some oil will have a tendency to flow into the joint whenever the supply of oil in the adjacent part of the joint is reduced for whatever reason. There would also be a flow of this oil into the joint to close the leak whenever air leaked through the joint from the outside.

45 As the horizontal surfaces 13 and 24 upon and about the switch pin wear against the horizontal surfaces 14 and 25 of the body pin and body and the switch tongue, which has also worn meantime, settles very slightly
50 in a vertical direction within the body, the

tapered plug 27 settles down farther in the tapered opening and is effective to recenter the heel, securing greater uniformity in the wear of the engaging surfaces upon the heel and body.

70 In assembling my invention, I fill the entire cavity 34 in the body pin with oil. I find that I get my best results with a fairly heavy oil which will not gum in cold weather. I have secured good results from
75 the so-called "black" or "well" oil of commerce, mixed with kerosene.

80 As the switch pin is lowered or dropped to place, the air within it is largely expelled before any of the oil has been forced out of the cavity in the body pin by the plug 27. When this plug enters the counterbore of the recess 31 and overflow of oil begins, the oil is expelled with more or less force according to the speed of downward movement of the heel. It spreads out, fan-like, filling first the upper part and ultimately all of the steadily decreasing space between the lower surface 32 of the plug flange and the upper surface 33 of the body pin. This
85 drives nearly all, if not all, of the remaining air out of this annular space and leaves it filled with oil when the parts come to rest. I may also put some oil initially in the lower part of the channel between the wall 9 of
90 the body and the body pin. This will usually not be desirable because it tends to trap the air within the heel and about the plug; and is also usually not necessary because the overflow from the body pin recess supplies
95 the oil desired in the channel and, in fact, throughout the joint. However, this channel offers an initial cavity for any additional oil desired.

100 Whether the channel be supplied with oil initially or not, the air in the channel is forced out by the entry of the heel pin and by oil.

105 The oil in the channel, whether placed there initially or overflowed into it, will be forced upwardly outside of the heel pin, between the surfaces 24 and 25, forming an air seal and lubricant not only at this point but throughout this outer part also of the joint. The quantity of oil, wherever placed, may be made sufficient to fill any annular spaces such as 21 or 22, which the convenience of grinding or the desirability of such reserves has led the designer to provide. These annular oil pockets may be used to hold a greater oil reserve to make up any loss and keep the surfaces reliably air sealed and lubricated, or to so distribute reserve oil supply as to have a reserve close to each part of the joint and to supply one or a series of
110 120 125 pool protections from air leakage. Any other spaces may be left for oil reservoirs for the same purpose.

130 Obviously, the annular space 22 will be of little benefit as a pool for reserve oil where

the flange 23 merges into a tongue having its lower surface in the same plane with the flange or below it unless other means be taken to maintain the oil level in the space.

5 The downward movement of the heel within the body by reason of wear supplies additional oil to the parts from within by forcing oil out of the recess 31. Another 10 feature of my invention provides so convenient and effective a method of maintaining the fluid level in the channel 22 that I have considered it unnecessary to illustrate any of the various other methods of so doing, which will occur to designers of switches.

15 In order to insure proper lubrication of the switch tongue and at the same time prevent intrusion of moisture and hardening of any dirt that settles within the switch bed, with their attendant evils of freezing and 20 interference with the movement of the switch tongue, I fill the tongue bed to an appreciable depth with oil, so that there shall always be sufficient oil to keep soft the dirt accumulated between intended cleaning 25 intervals. To insure this it is better to plan for free fluid oil at all times in addition to such oil as may be absorbed by the dirt accumulated. The depth of oil may readily be made sufficient to fill the channel 22 as 30 deeply as desired and keep any dirt in the channel soft, so that it will not obstruct the movement of the tongue. The oil in the tongue bed will lubricate the sides of the flange 23.

35 I believe that I am the first to provide an open considerable pool of oil for the purpose of receiving inevitable dirt and maintaining it in soft condition while at the same time lubricating a joint and preventing intrusion of moisture present in quantity; and that I am the first to utilize oil for the 40 reception of dirt and maintenance of the dirt in soft condition and exclusion of moisture in mechanism subjected to street surface 45 conditions.

In the black oil mixture which I use the proportion of kerosene to black oil varies according to the season, *i. e.*, with the temperature. In summer I use almost pure 50 black oil and in the coldest weather supply as much as 75% of kerosene.

55 When the parts are in place there will be little, if any air below the level of the surfaces 23, 24, and the close fit of the parts, as well as the length and reversed path of the tortuous passage provided, sealed by the intervening film of oil greatly retard air ingress as the switch tongue heel is withdrawn from the body. The result is that almost 60 the full atmospheric pressure over the heel is effective to resist accidental lifting of the heel.

65 Stability against tilting is given by the flange at the top of the heel pin and the bearing at its bottom as well as by the rela-

tively high central bearing of the plug 27 and the close fit provided for the entire heel pin externally and internally between the body and body plug.

It will be seen that I provide two pairs of 70 horizontal annular bearing surfaces, 13 against 14 and 24 against 25, to receive the weight of the trains and divide vertical wear, and four pairs of lateral bearing surfaces, corresponding to the diameters of the 75 outside of the heel and of the flange, body pin and tapered pin, to receive side thrust and lateral wear, greatly stiffening against side strain and tilting and reducing the extent of abrasion by wear. In order to provide for the withdrawal of the tongue and heel, I provide preferably undercut apertures 35 in the side of this member placed at such a distance from the ends as that the weight of the tongue at the left of the apertures in Fig. 2 shall balance the weight of the tongue and heel to the right thereof, plus the air pressure upon the heel made effective by the vacuum conditions within when the heel is being withdrawn; and I supply a special tool for engaging the tongue within these depressions and lifting it. This tool comprises the yoke 36, any suitable lifting mechanism, here shown as bolt 37 and nut 38 operated by lever arms 39, and a link 40 85 to which the hooks 41 are pivoted at 42. The link is pivoted to the bolt at 43 so as to adjust the pull to the position of and strain upon the tongue. The ends 44 of the hook are shown as undercut to correspond with 90 the openings and the total depth of each hook from its point to the edge 45 must not exceed the space available between the tongue and side of the tongue bed at this point when the tongue is thrown to the extreme opposite side from that at which the hook is being entered. The operation of this lifting mechanism will be obvious from the illustration in Fig. 5.

It will be evident that a part of the benefit of my invention may be obtained by portions of the construction of heel pin and cooperating body, without other parts thereof, or by other constructions equivalent thereto, in view of the disclosure herein; that my oil seal may be used even without distribution of the oil initially from the interior of the heel, to some advantage and with widely different mechanical constructions; that my open pool of oil for prevention of concentration and hardening of dirt in the tongue bed may be of advantage independently of the character of heel joint, even without the oil seal; and that the open pool is of great advantage in maintaining lubrication and oil seal within a heel joint of whatever character.

It will be evident that the angle of taper of the plug 27 is the same as that of the gage side of the rail head. While this is ad- 130

vantageous as a recognized safe angle of taper upon which wheel flanges will not mount and with which there will be no tendency to wedge the plug upwardly because of side strain due to traffic conditions, its selection was guided also by the angle of upward and outward flow needed to secure a desirable distribution of oil throughout the upper part of the space between surfaces 32 and 33 so that the air should be reliably expelled ahead of the oil.

Having thus described my invention, what I claim as new and desire to secure by Letters Patent is:—

15 1. In a device of the character stated, a switch tongue and heel having a depending approximately cylindrical heel pin open at the bottom, in combination with a body having an approximately cylindrical annular 20 channel against whose side walls the pin fits.

2. In a device of the character stated, a switch tongue and heel having a depending approximately cylindrical heel pin open at the bottom forming a reentrant surface, in combination with a body having an approximately cylindrical annular channel against whose side walls the pin fits and oil between the parts.

30 3. In a device of the character stated, a switch tongue and heel having a depending, substantially cylindrical heel pin and a laterally extending flange at the top of the heel, in combination with a switch body having a horizontal ledge upon which the flange rests and an annular channel whose sides engage the substantially cylindrical heel.

4. In a device of the character stated, a switch tongue and heel, having a depending, substantially cylindrical heel pin and a laterally extending flange at the top of the heel, in combination with a switch body having a horizontal ledge upon which the flange rests, an annular channel whose sides engage those of the heel and oil between the adjoining surfaces of the heel and flange providing a seal between them and the body.

5. In a device of the character stated, a switch tongue, a depending heel thereon, a body within which the heel fits forming a joint therewith and oil filling the joint, there being an annular pocket in one of the parts above the bottom of the joint adapted to store oil and feed it to the joint, as required.

6. In a device of the character stated, a switch tongue, a depending heel thereon having in section a reentrant contour, in combination with a body fitting the contour of the heel and oil substantially filling the space between the body and heel and sealing the abutting surfaces against air and moisture inlet.

7. In a device of the character stated, a switch tongue, a depending heel thereon

having a recessed lower end and, within the recess a relatively projecting portion, in combination with a switch body having a contour substantially fitting the contour of the heel, including a recess for the projecting part, and oil within said recess spread by the projection.

8. In a device of the character stated, a switch tongue, having a depending hollow heel thereon, a switch body fitting the outer 75 part of the heel and entering the hollow thereof and a tapered centering plug within the hollow, fitting within a recess in the body.

9. In a device of the character stated, a switch tongue terminating in a flange, a hollow heel upon the tongue concentric with the flange and a body fitting the flange and exterior and interior of the hollow heel.

10. In a device of the character stated, a switch tongue having an annular flange, a hollow heel depending therefrom concentric with the flange, a body fitting the horizontal surface of said flange and the outer contour of the heel, a projection upon the body entering the hollow of the heel, and oil within the interior of the heel and above the level of said projection.

11. In a device of the character stated, a switch tongue having a hollow depending 95 heel pin in combination with a switch body having an annular channel with whose walls the outside and inside walls of the pin are adapted to engage.

12. In a device of the character stated, a switch tongue and heel having at the heel a depending cylindrical pin and a concentric tapered plug therein, in combination with a body having an upwardly extending pin fitting the interior of the cylinder of the heel 105 pin and fitted to receive and guide the tapered plug.

13. In a device of the character stated, a tongue and heel having a depending substantially cylindrical pin open at the bottom and a flange at the top of the pin, in combination with a body having surfaces closely fitting the outer and inner cylindrical surfaces of the pin and the bottom of the flange and oil within the pin and between the surfaces.

14. In a device of the character stated, a switch tongue and heel having a flange about the upper heel surface and a tapered plug depending from the portion of the heel to which it is attached, in combination with a body having surfaces engaged by the under and lateral faces of said flange and fitting the taper of the plug.

15. In a device of the character stated, a tongue and heel having a depending substantially cylindrical hollow heel pin, a flange about the upper surface of the pin and a central depending tapered plug within the pin, in combination with a switch body having an upper surface engaging the under 125 130

surface of the flange and the lateral surface of the flange, annularly channeled to receive the depending pin, engaging its inner and outer surfaces, and centrally fitted to receive and guide the tapered plug.

16. In a device of the character stated, a switch tongue and heel having at the heel thereof a depending hollow substantially cylindrical pin in combination with a switch body annularly channeled to receive and closely fit the outside and inside of the pin and oil between the surfaces of the pin and body forming a substantially air tight joint

therebetween extending within the body of the pin.

17. In a device of the character stated, a switch body having a switch bed therein, a tongue swinging in the bed, a depending heel pin at the heel of the tongue and oil within the heel pin joint and covering the bed to an appreciable depth to form a fluid pool therein.

JOHN GREENWALD HARTLEY.
